UNITED STATES PATENT OFFICE.

JOHN CEDARSTROM, OF NEW YORK, N. Y., ASSIGNOR, BY DIRECT AND MESNE ASSIGNMENTS, TO THE UNITED STATES AERATING FOUNTAIN COMPANY, OF SAME PLACE.

APPARATUS FOR DISPENSING AERATED LIQUIDS.

SPECIFICATION forming part of Letters Patent No. 633,802, dated September 26, 1899.

Application filed December 14, 1898. Serial No. 699,229. (No model.)

To all whom it may concern:

Be it known that I, JOHN CEDARSTROM, a citizen of the United States, residing in the city and State of New York, have invented 5 new and useful Improvements in Apparatus for Dispensing Aerated Liquids, which are fully set forth in the following specification.

This invention relates to apparatus for dispensing aerated liquids, and is an improvement 10 on the apparatus disclosed in United States Letters Patent No. 476,760, granted June 7, 1892, to Panchaud and Temple.

The particular objects of the present invention are to improve the valve, rendering it 15 tighter, more lasting, and more easily fastened; to adapt the apparatus for use with soda-water fountains, where it is desirable to stir up the flavoring-syrups, and to provide certain other features of improvement, as 20 hereinafter set forth.

Owing to the pressure of the confined gas it is necessary that all joints, in particular that formed by meeting surfaces of the valve and valve-seat, be as tight as possible. Experience shows, however, that when the valve 25 is crowded down closely upon the valve-seat there ensues, owing to attrition, a disintegration and disruption of the surface of the washer on the face of the valve that is particularly noticeable along the edges of the 30 slots shown in Fig. 4 of the patent and marked *k* and *b*. This difficulty is overcome in the present invention by locating the transverse passage-ways of the valve within the metal, 35 while the washer has instead of slots merely the necessary perforations, thus reducing the extent of edge which forms the weak portion of the washer heretofore used. It is found more convenient and better results can be 40 obtained by locating the washer in an angular seat in the face of the valve-seat instead of in a circular seat in the face of the valve.

In the patented invention when for any reason it is desired to unseat the valve or to 45 tighten it it is necessary to employ a wrench to turn the angular head of the block that holds the valve in place. The present invention comprises an auxiliary tightener by which, after the block is screwed down, the

valve itself may be tightened or loosened 50 without the aid of any other tool.

Again, the patented invention discharges the contents of its "intermediate receptacle" 55 into the drinking-glass placed to receive it at one gulp, as it were, through the aperture *h*, Figs. 1 and 2, of the patent. It is desirable in soda-water fountains to make provision for a needle-like stream first that stirs up the flavoring-syrups in the bottom of the drinking vessel and then the larger stream that 60 contains the bulk of the aerated liquid. The present invention allows both of these results to be accomplished at one turn of the operating-handle by providing a comparatively minute orifice through the plug closing the bottom of the intermediate receptacle. 65

Referring now to the drawings annexed hereto and made a part of this specification, Figure 1 is a vertical section through the valve-seat, showing the valve in elevation 70 and the auxiliary tightener partly broken away. Fig. 2 is a cross-section of the valve-seat and a plan of the washer. Fig. 3 is a bottom plan of the valve; and Fig. 4 is a vertical section through the spring-tube, the hollow piston-rod, and the plug, showing the plug-stem partly in elevation. 75

A is the valve-seat, in which is located the washer *A'*, preferably of hexagonal outline, as shown in Fig. 2. The aperture *a* communicates with the reservoir through the passage shown in Fig. 1, aperture *a'* communicates with the intermediate receptacle through the tube *H*, and apertures *a'' a'''* communicate one directly with the intermediate receptacle and 80 the other with the external atmosphere, all just as shown in the Patent No. 476,760. Valve *B* is held in the valve-seat by block *C*, screwed into the latter. On the bottom of the valve-head is the radial channel *b* and the channel *b'*. (Indicated in Fig. 3 by dotted lines.) Metal plate *B'* is secured to the bottom of the valve-head and is provided with apertures *b²*, *b³* and *b⁴ b⁵*. 85

The operation of the apparatus is precisely 90 as described in the patent, and need not be described here.

I have shown the washer as located in the

valve-seat, but it may be placed in the surface of the valve in place of plate B'. The advantage of its present location is that it may be made larger without enlarging the 5 other parts; besides the channels b b' are protected by metal instead of by the washer. The superiority of either construction over that shown in the patent lies in the fact that the meeting surfaces have apertures merely, 10 instead of elongated slots whose edges are soon disintegrated and worn away. If desired, plate B' may be dispensed with and passage-ways b b' made in the piece B, the spirit of the invention lying in covering up 15 the edges of the passage-ways so as to prevent the edges if in the metal from cutting the washer or if in the washer from being worn off.

It is desirable to provide the stop A² in the valve-seat, and the stops B² B³ on the valve 20 (see Fig. 3 and dotted lines, Fig. 2) so adjusted as to arrest the valve in either of its two operative positions.

The hollow screw D surrounds the shank of the valve and is screwed down into block 25 C, as shown, by means of milled head D'. The bottom of D presses upon the offset shoulder E of the valve through the intermediate strong spring-washer E'. If for any reason the meeting faces of A' and B' do not 30 form a tight enough joint, all that is necessary is to turn the head D', and thus press B' more tightly against A'. I may provide also the jam-nut D².

To adapt the apparatus to soda-water fountains, I provide an outlet comparatively 35 smaller than the inlet, whereby while the intermediate receptacle is filling a portion of the liquid may pass immediately into the drinking vessel. A very convenient way of 40 accomplishing this is to cut one or more longitudinal grooves f in the lower end of plug-stem F and provide in plug G an aperture g communicating with f. When the handle of the valve is turned in the proper direction, 45 the liquid passes from the reservoir through passage a, channel b, passage-way a', and the interior of H and plunger I. All this is just as in the patent, and (as in the patent) the

pressure automatically forces the plug into the orifice at the bottom of the intermediate 50 receptacle, after which the receptacle itself if filled; but in the present invention, while this operation is going on, at the same time a comparatively small portion of the liquid passes from the interior of hollow piston-tube 55 I, through groove f and aperture g into the drinking-glass placed to receive it, in the form of a fine needle stream that stirs up and thoroughly disseminates the syrup or cream in the bottom of the glass. 60

To empty the intermediate receptacle, turn the handle of the valve, as in the patent, and the gas escaping, as in the patented apparatus, releases the plug, and the contents of the intermediate receptacle are discharged into 65 the drinking-glass.

The simplicity and ease of manipulation are noteworthy. Turn the handle in one direction and the fine stream is directed into the drinking-glass while the intermediate receptacle is filling up. Turn it back and the 70 glass is filled.

It is obvious that modifications could be made in the details of construction of the several parts of the apparatus and that, if desired, some of the improvements described could be used without others without in either case departing from the spirit of the invention. 75

Having thus described my invention, what I claim is— 80

In a liquid-dispensing apparatus of the type described, the combination with the closure-plug having a perforation opening into the outer air, and the plug-stem having a longitudinal groove communicating with the perforation, the outlet so formed being smaller than the inlet for the liquid, substantially as described. 85

In testimony whereof I have signed this 90 specification in the presence of two subscribing witnesses.

JOHN CEDARSTROM.
